UNITED STATES PATENT OFFICE.

DODGER L. KITTRELL, OF NASHVILLE, TENNESSEE.

CHECK-CONTROLLED APPARATUS.

1,173,003.

Specification of Letters Patent. Patented Feb. 22, 1916.

Application filed October 29, 1915. Serial No. 58,686.

To all whom it may concern:

Be it known that I, DODGER L. KITTRELL, a citizen of the United States, residing at Nashville, in the county of Davidson and 5 State of Tennessee, have invented new and useful Improvements in Check-Controlled Apparatus, of which the following is a specification.

This invention relates to improvements in 10 check controlled apparatus and has particular application to apparatus for controlling the operation of pumps for vending gasoline, although I wish it to be understood that my invention, in its useful application, 15 may be used in connection with apparatus other than pumps.

In carrying out the present invention, it 20 is my purpose to provide check controlled apparatus which will be found especially useful in controlling pumps for dispensing gasoline and whereby the pump may be operated to deliver the gasoline only after a coin of the proper denomination has been inserted in the apparatus and whereby a 25 predetermined quantity only of the gasoline will be delivered to the purchaser.

It is also my purpose to provide apparatus of the class described which will operate 30 efficiently and effectively under all conditions to control the operation of the pump or other apparatus, which will be capable of a variety of uses and wherein the component parts will be so arranged and correlated as to reduce the possibility of derangement to a minimum.

With the above and other objects in view, the invention consists in the construction, combination and arrangement of parts hereinafter set forth in and falling within the 40 scope of the claims.

In the accompanying drawings; Figure 1 is a view in side elevation of check controlled apparatus constructed in accordance with the present invention, the same being 45 shown as connected with a gasoline pump. Fig. 2 is a vertical sectional view through the casing of the apparatus, the mechanism being shown in side elevation and in normal position. Fig. 3 is a similar view showing 50 the parts in the positions they occupy when a coin is inserted in the casing. Fig. 4 is a cross sectional view on the line 4—4 of Fig. 2. Fig. 5 is a similar view on the line 5—5 of Fig. 2. Fig. 6 is an enlarged fragmentary vertical sectional view through the apparatus.

Referring now to the drawings in detail, 1 designates a base constructed of any suitable material, while 2 indicates a supporting frame arranged at one end of the base 1 and 60 upstanding therefrom and in the form of an inverted U. Arranged across the face of the inverted U-shaped frame and suitably fastened to the legs thereof adjacent to the upper end of the frame is a cross bar 3. 65 Slidably mounted within vertically alining bearings carried by the upper end of the frame 2 and the cross bar 3 respectively is a vertical rod 4 capable of vertical sliding movement and having the lower end thereof 70 connected with the upper extremity of the piston rod 5 of the pump 6, the piston rod working within an opening formed in the base 1. Formed on one edge of the rod 4 are teeth 7, while pivoted upon the cross bar 3 is a lever 8 having the lower end formed with a dog 9 and the upper end weighted as at 10 and acting to hold the dog end of the lever normally in engagement with the teeth 7. Formed upon the opposite edge of 75 the bar 4 are teeth 11 and pivoted upon the cross bar 3 adjacent to the teeth 11 is a dog 12 normally held out of engagement with the adjacent ratchet teeth 11. The teeth 11 are arranged reversely to the teeth 7. Also 80 formed on one edge of the rod 4 is a series of gear teeth 13 and meshing with the teeth 13 is a pinion 14 mounted upon a shaft journaled in the upper end of the frame 2 and connected to one end of this shaft is a crank 90 handle 15 whereby the pinion may be rotated to slide the rod. Secured to the base 1 and projecting upwardly therefrom is a vertical standard disposed adjacent to one edge of the frame 2 and pivoted upon the 95 upper end of the standard 16 is a horizontal beam 17. Secured to one end of the beam 17 is a yoke 18 and pivoted between the limbs of the yoke 18 is a coin receptacle 19 provided with a downwardly projecting curved wing 20. The opposite end of the beam 17 is offset downwardly as at 21 and slidably mounted upon the offset portion of the beam is a weight 22 and balancing the coin receptacle 19.

23 designates a vertical rod having the lower end thereof slidably mounted within an opening in the base and the upper end slidably mounted in an opening in the upper extremity of the frame 2. Adjustably 100 mounted upon the rod 23 is a pin 24 disposed adjacent to the end of the offset por-

tion 21 of the beam 19 and normally holding such end of the beam against downward movement under the action of the counterweight 22. Also upstanding from the base 1 adjacent to the yoke end of the beam and below such end is a short standard 25 and pivoted upon the upper end of the standard 25 is a trip 26 connected by means of a wire 27 with one leg of a bell crank lever 28 pivoted upon the leg of the frame 2 adjacent to the opposite end portion of the beam. Pivoted to the remaining leg of the bell crank lever and projecting upwardly therefrom is a link 29 having the upper end thereof connected with an arm 29' secured to the rod 23. Secured to the lower end of the rod 4 and projecting outwardly therefrom and loosely surrounding the rod 23 is a lug 32. 36 designates an arm secured to the beam 17 at the fulcrum point of such beam and projecting upwardly therefrom, while 37 indicates a wire connecting the upper end of the arm 36 with one end of a link 37'. The other end of the link 37' is connected through a pin 25 and slot connection 30 with the dog end of the lever 8, and by a wire 31 with the dog 12.

33 designates a casing inclosing the mechanism just described and formed with a coin slot 34 from which extends a coin chute 35 leading to the receptacle 19.

In practice, the receptacle 19 is normally disposed contiguous to the lower end of the chute 35, while the dog end of the lever 8 holds the rod 4 normally at its limit of downward movement and prevents movement of the rod under the action of the handle. When it is desired to actuate the rod 4 a coin of the proper denomination is deposited in the slot 34 and falls down the chute 40 35 into the receptacle 19 and when the coin enters the receptacle the counterweight 22 is overbalanced and the beam 17 swung about its pivotal connection with the standard 16 and in this movement of the beam 17 the 45 arm 36 pulls upon the wire 37 and so actuates the link 37' with the effect to move the dog end of the lever 8 out of engagement with the teeth 7 and the pawl 12 into engagement with the teeth 11. The crank 50 handle 15 may now be rotated and in the rotation of the crank handle the rod 4 will be moved in one direction to move the pump piston from one end of the cylinder to the other. As the rod 4 moves upwardly the 55 lug 32 slides upwardly along the rod 23 and engages the pin 24 with the effect to elevate such rod 23 and in the continued upward movement of the rod, the pin 24 is carried into engagement with the adjacent end of the beam 17 and swings the yoke end of the beam downwardly. Simultaneously with the downward movement of the yoke end of the beam 17, the trip 26 is swung upwardly through the medium of the arm 29', link 29, 60 bell crank lever 28, and the wire 27, incident

to the upward movement of the rod 23 to which the arm 29' is connected, and in the downward movement of the yoke end of the beam 17, and the upward movement of the trip 26, the wing 20 is struck by the trip 70 with the effect to tilt the coin receptacle to discharge the coin therefrom.

Upon the discharge of the coin from the receptacle 19 the counterweight 22 swings the beam 17 in the reverse direction and the 75 arm 36 and wire 37 restore the dogs to normal positions, thereby permitting the rod 4 to be moved in the opposite direction under the action of the crank handle to move the piston toward the opposite end of the cylinder. Upon the movement of the pawls to normal positions the bell crank lever and trip 26 are likewise restored to their original positions so that the above cycle of operations may be repeated when another coin is 85 deposited in the slot.

While I have herein shown and described one preferred form of my invention by way of illustration, I wish it to be understood that I do not limit or confine myself to the 90 precise details of construction herein described and delineated, as modification and variation may be made within the scope of the claims and without departing from the spirit of the invention. 95

I claim:

1. In check controlled apparatus, a rod capable of sliding movement and having rack teeth formed on opposite edges thereof, the teeth on one edge of the bar being arranged reversely to those on the other edge, a lever normally engaging the teeth on one edge of the bar and holding the bar against sliding movement in one direction, a pawl disposed at the opposite edge of the bar and normally out of engagement with the teeth thereon and adapted to coöperate with the adjacent rack teeth, check controlled means for moving the lever out of engagement with the teeth to permit movement of the bar in 100 one direction and to engage the pawl with the adjacent teeth to prevent movement of the bar in the opposite direction, and means operable from said bar in the movement thereof when relieved of the influence of the 105 lever to restore both the lever and the pawl to normal positions so that the direction of movement of the bar may be reversed.

2. In check controlled apparatus, a rod capable of sliding movement and having 120 rack teeth formed on opposite edges thereof, the teeth on one edge of the bar being arranged reversely to those on the other edge, a lever normally engaging the teeth on one edge of the bar and holding the bar against sliding movement in one direction, a pawl disposed at the opposite edge of the bar and normally out of engagement with the teeth thereon and adapted to coöperate with the adjacent rack teeth, check con- 125

trolled means for moving the lever out of engagement with the teeth to permit movement of the bar in one direction and to engage the pawl with the adjacent teeth to prevent movement of the bar in the opposite direction, means operable from said bar in the movement thereof when relieved of the influence of the lever to restore both the lever and the pawl to normal positions so that the direction of movement of the bar may be reversed, and hand operated means for sliding said bar.

3. In check controlled apparatus, a rod capable of sliding movement and having rack teeth formed on opposite edges thereof, the teeth on one edge of the bar being arranged reversely to those on the other edge, a lever normally engaging the teeth on one edge of the bar and holding the bar against sliding movement in one direction, a pawl disposed at the opposite edge of the bar and

normally out of engagement with the teeth thereon and adapted to coöperate with the adjacent rack teeth, means operable under the weight of a coin to move the lever out of engagement with the adjacent teeth to permit movement of the bar in one direction and to engage the pawl with the adjacent teeth to hold the bar against movement in the reverse direction, and means operable from said bar in the movement thereof when relieved of the influence of the lever to discharge the coin from the first-mentioned means so that the lever and the pawl may be restored to normal positions and the direction of movement of the bar reversed.

In testimony whereof I affix my signature in presence of two witnesses.

DODGER L. KITTRILL.
